UNITED STATES PATENT OFFICE.

HOWARD LYON, OF GLOUCESTER CITY, NEW JERSEY, ASSIGNOR TO WELSBACH LIGHT COMPANY, A CORPORATION OF NEW JERSEY.

METHOD AND MEANS FOR GAS IGNITION.

1,118,940.

Specification of Letters Patent.

Patented Dec. 1, 1914.

Application filed February 2, 1910. Serial No. 541,600.

To all whom it may concern:

- Be it known that I, HOWARD LYON, a citizen of the United States, residing at Gloucester City, in the county of Camden and State of New Jersey, have invented certain new and useful Improvements in Methods and Means for Gas Ignition, of which the following is a description.
- My invention relates to a novel method and means for igniting a jet or current of combustible gas, for example, ordinary illuminating gas, or combustible vapor such as alcohol, gasolene, etc., all of which are hereinafter referred to simply as gas.
- It has been proposed heretofore to ignite gas currents by means of a wire rendered incandescent by an electric current, said wire being situated in or close to the outlet of the jet to be ignited or to the outlet of a small by-pass or auxiliary jet which is itself capable of igniting the main jet. All of such devices with which I am familiar have been defective and impractical for the following reasons: A current of gas mixed with air and surrounded with air such as exists in the vicinity of the outlet of an unlighted gas burner is not a uniform mixture,—at one point it may be rich, at another point weak or lean. If the ignition wire is situated at a point where the mixture is too lean, the gas will not ignite, and if at a point where the mixture is very rich the gas will ignite and will at the same time develop such a high temperature that the wire will burn up within a short time, that is after a comparatively few ignitions. If further the wire be located at a point where the combustible gas is unmixed or slightly mixed with air there can of course be no ignition. Furthermore, if by experimenting with gas of a given richness a person determines a position where he may place the wire so that it will be in a mixture that is neither too rich nor too lean, he will find that upon varying the pressure (either increasing or diminishing it) the wire will no longer be situated in a favorable position but will be where the gas is either too rich or too lean. And moreover, if instead of varying the pressure he maintains it constant but varies the quality of the gas (making it either richer or leaner) he will find

that the position of the wire is no longer favorable and that it will either fail to ignite or will soon burn up.

55

After careful study and experimentation, I have been able to analyze the problem above presented, to determine the necessary conditions governing the location of the ignition wire and have invented a successful method and apparatus for igniting a gas jet or current which form the subject matter of the present application and are especially well adapted for the ignition of inverted gas burners. In practising the said method 60 I mount an ignition wire or filament at a distance from the burner head, liberate the gas into the body of air with which the lamp is normally filled, direct the same into the vicinity of the filament, and simultaneously dilute the mixture thus formed with air and energize the filament. When the gas is first turned on, the filament (preferably a wire of platinum or platinum alloy) is surrounded by air. This air is then replaced by a 65 mixture of gas and air which becomes progressively richer as the gas continues to fill the lamp. The time quickly arrives when the richness is sufficient to cause the gas to ignite, whereupon the usual explosion takes 70 place, the gas in the lamp is consumed and the jet burns at the burner head, thus automatically cutting off all gas from the ignition filament. This explosion of course takes place at the very moment that an inflammable or critical mixture reaches the filament, and a rich mixture can therefore never reach the filament. By reason of this fact, the ignition filament is protected against the development of excessive temperatures 75 which would cause the same to burn up after 80 comparatively few operations. It is immaterial what may be the pressure of the gas supply or its quality. An increase of pressure or of richness or both means merely a 85 shorter interval before an inflammable or critical mixture reaches the ignition filament, and vice versa, a decrease of pressure or of richness or both merely increases the interval required for the proper mixture to 90 reach the ignition filament.

In order that the invention may be more fully understood, reference is hereby made to the accompanying drawing of which—

Figure 1 is a side elevation, partly in section, showing my improved apparatus applied to a well known form of inverted incandescent gas burner. Fig. 2 is an enlarged longitudinal section of the ignition tube of Fig. 1. Fig. 3 is a side elevation of the same, partly in section in a plane at right angles to the plane of Fig. 2. Fig. 4 is a section on line 4-4 of Fig. 1, and Fig. 5 is a bottom plan of Fig. 4.

10 The gas burner of Fig. 1 comprises an inverted U-shaped supply tube *a* which forms a support for the lamp and is provided with the usual gas check *b*, air inlets *c*, flash diaphragm *d*, globe holder *e*, Bunsen tube *f*, and mantle holder *g*. The globe holder *e* is in the form of a canopy or inverted funnel having large openings *h* for discharging the heated products of combustion. Near the center of the globe holder and at substantially the highest point is an opening 1 above which is mounted a nipple 2 having a flange 3 which is secured by rivets (not shown) to the canopy *e*, the bore of said nipple registering with said opening. Upon the nipple 2 is mounted a vertical tube 4 secured by a set screw 5. The bore or interior of said tube forms an ignition chamber. Extending diametrically across said tube and through the walls thereof at a point near its lower end is an air inlet tube 6, Figs. 2 and 3. This tube or baffle is cut away as shown at 7 forming a trough the bottom of which in cross section 30 is a semicircle.

35 Near the upper end of the tube 4 is a pair of oppositely disposed openings 8. These openings prevent an excessive accumulation of gas before ignition, and after ignition 40 allow the escape of the products of combustion in a continuous stream or current which causes currents of air to be drawn in through the openings 19 hereinafter referred to. The upper end of 45 the tube 4 is closed by a plug composed of a flanged metal sleeve 9 secured by a set screw 10, and an insulating bushing 11 set therein and through which passes a headed conducting bolt 12 secured by a nut 13. A 50 nut 14 is also threaded on said bolt and secures one end of a conducting wire 15. A very fine wire 16 of platinum or platinum alloy is secured at its ends to the supporting conductors 17 and 18 one of which is soldered 55 to the head of the bolt 12 and the other to the sleeve 9. The wire or filament 16 is situated centrally with respect to the tube 4 and is so disposed with respect to air inlets 19 and 20 as to be bathed in air to a 60 large extent. At the same time it is protected by the baffle 6 against the hot products of combustion rising from the lamp after ignition. The baffle 6 also protects the filament against excessive temperatures 65 during ignition due to mixtures of too great

richness. The hottest portion of the filament during ignition, which may be termed its active portion, is usually at its center on account of the flow of heat from the filament to the leading in wires or supporting conductors 17 and 18. The width of the baffle is substantially greater than that of the active portion of the filament, whereby the filament, and particularly its active portion, is protected against excessive temperatures during ignition, by reason of the fact that the baffle is so placed as to permit only a small percentage of the ascending gas to approach the filament and at the same time to permit the free access thereto of atmospheric air entering through the inlets 19 and 20. The baffle together with said inlets produce an ignitable mixture of minimum richness.

70 The gas controlling cock may be of any desired form, but is preferably constructed so as to simultaneously admit gas to the pipe *a* and complete an electrical circuit through the wire 15. As shown it comprises a body 21 having the usual key 22, 80 from which depends a pin 23 of insulating material. There is a ring 24 of insulating material mounted on the body 21, and a conducting ring 25 on said ring 24. Springs 26 and 27 are secured to said ring 25 by screws 28 and 29, the latter of which acts as a binding post for a wire connected to one pole of an electric battery, one dry cell being sufficient for the purpose. The other pole of the battery is grounded or 90 connected to the gas supply pipe. The free end of the spring 26 extends outwardly in position to be engaged by the pin 23. An insulating block 40 is secured to the body 21 by a screw 31, and a contact 32 is mounted 105 thereon in position to be engaged by the spring 27. A binding post 33 secures the wire 15 to said contact 32.

95 The device is operated as follows: The key of the cock is turned slightly beyond the 110 position of Figs. 4 and 5 so as to cause the spring to press against the contact 32 and complete an electric circuit from the battery through the ring 25, spring 27, contact 32, wire 15, bolt 12, wires 17, 16 and 18 to 115 the ground and back to the battery. At the same time the gas is admitted to the lamp and flows from the burner head of the Bunsen tube *f*. The stream of gas rises into the top of the canopy 2 and a portion of it flows through the opening 1 into the ignition chamber within the tube 4. Passing around the tube 6 it flows on upward encountering the wire 16 which is bathed in air entering through the openings 19 and 20. The electric current which is at that time passing through the wire 16 is preferably of a strength which is insufficient of itself to heat the wire to the kindling temperature of the gas, but is sufficient to initiate catalytic ac- 120

125

130

tion of the stream of gas upon the said wire. The catalytic action quickly brings the wire to the kindling temperature of the gas whereupon the gas is ignited and the flame immediately consumes all of the gas in the lamp and thereafter burns at the burner head of the Bunsen tube *f* in the usual manner. Obviously the flame thus established consumes all of the gas issuing from said burner head and thereby automatically cuts off all gas from the ignition tube. The heated products of combustion pass out of the lamp in the usual manner through one or more openings *h*, only a small portion passing through the opening *l* into the ignition device. Such products, however, set up a current through the tube issuing at the openings *g* which causes air to be drawn in through the openings *19* and *20* thereby cooling the wire *16* and preventing it from being injured by the heated products of combustion, and also by reason of the inflow of oxygen making the wire more sensitive to future ignitions. The oxygen appears to revivify or energize the platinum, making it more sensitive to the catalytic action hereinbefore referred to. After the lamp is ignited the key *22* is released and the spring *26* thereupon moves the same back sufficiently to open the electric circuit as shown in Figs. 4 and 5.

Having now described my invention, what I claim is:

1. The method of igniting a current of gas which consists in warming a catalytic filament by an electric current whereby its catalytic activity is increased and directing the gas into the vicinity of but at one side of the filament, said gas current causing a current of air to be aspirated or entrained directly toward the filament, whereby the richness of the mixture in the immediate vicinity of the filament is minimized, substantially as set forth.
2. The method of regenerating the catalytic filament of a gas ignition chamber which consists in directing toward said filament a current of atmospheric air and a distinct and independent current of heated products of combustion, and in deflecting said last named current away from the filament and into the air current as it approaches the filament, substantially as set forth.
3. In a gas lamp, ignition means comprising a catalytic filament, means for applying an electric current thereto whereby its catalytic activity is increased, an ignition chamber within which the filament is situated, said chamber having one or more air inlets adjacent the filament, and means for directing the gas current into the vicinity of the filament in such a way that a direct approach thereto is prevented and air is aspirated or entrained inward toward the fila-

ment through the inlet or inlets, substantially as set forth.

4. In a gas lamp, the combination of a burner head, a canopy above the same and provided with an aperture, an ignition chamber having a gas inlet communicating with said aperture, a gas outlet at or near the top thereof, one or more air inlets in its intermediate portion, and a heated filament adjacent thereto, said moving gas and heated filament acting in conjunction to draw air through said air inlet or inlets.

5. In a gas lamp, the combination of a burner head, a canopy above the same and having an aperture eccentric thereto, an ignition chamber in communication with said aperture, a filament situated within the ignition chamber, means for applying an electric current thereto and an air inlet adjacent said filament.

6. A gas lamp comprising a burner head, a supply pipe, a canopy surrounding said supply pipe above the level of the burner head, an opening in said canopy out of alignment with said burner head, an ignition chamber communicating with said opening, and having an inlet opening directly to the atmosphere, a filament within said ignition chamber adjacent said inlet, and means for applying an electric current thereto, substantially as set forth.

7. An ignition tube, a transverse member within the bore thereof and of smaller area than said bore, a conducting filament situated immediately above said transverse member and protected thereby against access of an excessively rich mixture and means for applying an electric current thereto.

8. An ignition tube, a transverse member within the bore thereof and of smaller area than said bore, a conducting filament situated immediately above said transverse member and protected thereby against access of an excessively rich mixture, means for applying an electric current thereto, and one or more air inlet openings in the wall of said tube adjacent said wire.

9. An ignition tube, a smaller tube extending transversely thereto through the walls thereof, a portion of said smaller tube being cut away, and a conducting filament situated above the bottom of said transverse tube and in position to receive air drawn into said transverse tube.

10. An ignition tube, a smaller tube extending transversely thereto, the upper portion of said smaller tube being cut away to form an air inlet, and a conducting filament situated near said air inlet and above the uncut portion of the smaller tube.

11. An ignition tube, a transverse trough-shaped member within the bore thereof, and a conducting filament adjacent the open side of said trough and extending in the same general direction as the edges thereof.

12. An ignition tube having one or more air inlets in the walls thereof, a transverse trough-shaped member within the bore thereof adjacent said air inlet, and a conducting filament adjacent the open side of said trough and extending in the same general direction as the edges thereof.
13. An ignition tube, a conductive filament mounted therein, a baffle for protecting said filament and of smaller area than the bore of said tube and means for admitting air to said filament and for permitting the discharge of products of combustion from said tube.
14. An ignition tube, a conductive filament mounted therein, a baffle for protecting the same and of smaller area than the bore of said tube, one or more air inlets adjacent said filament, said tube having additional openings for admitting and discharging gases.
15. In a gas lamp, a burner-head, an ignition tube situated above the level of the same, means for directing into said tube gases issuing from the burner-head, one or more openings adjacent the upper end of the tube for the discharge of said gases, a conductive filament within said tube, and one or more air inlets adjacent said filament.
16. A gas lamp comprising a burner-head, a canopy above the level of the same, an aperture in said canopy eccentric thereto, a chamber communicating with said aperture and having an air inlet above the canopy, and ignition means within said chamber adjacent said inlet, substantially as set forth.
17. In a gas lamp, an inverted cup-shaped canopy having an aperture near its top, an igniter comprising a body having an inlet and an outlet at a higher level than the inlet, a filament within said body, connections for applying an electric current to said filament, and means for securing said body to said canopy with its inlet in alinement with said aperture, substantially as set forth.
18. In a gas lamp, a support, an inverted cup-shaped canopy carried thereby and having an aperture near its top, a tubular igniter open at the bottom and having an outlet above the level thereof, and means for securing said igniter to said canopy independently of said support in an upright position with its bore in alinement with said aperture and its outlet outside of the canopy, said igniter comprising a filament and connections for applying an electric current thereto, substantially as set forth.
19. In a gas lamp, a gas supply having an outlet, an ignition chamber having an inlet in the path of gas issuing from said outlet, an ignition filament within said chamber, and a baffle close to said filament and between it and said gas outlet, the width of said baffle being substantially greater than 65 that of the active portion of said filament whereby the latter is protected against excessive temperatures during ignition, substantially as set forth.
20. In a gas lamp, a gas supply having an outlet, an ignition chamber having an inlet in the path of gas issuing from said outlet, an ignition filament within said chamber, a baffle between said filament and said gas outlet, and one or more inlets adjacent said filament and opening directly to the atmosphere for admission of atmospheric air thereto, substantially as set forth.
21. An igniter having an ignition chamber, a filament therein, means for applying an electric current thereto, and a baffle close to said filament and between it and the gas supply, the width of said baffle being substantially greater than that of the active portion of said filament, substantially as set forth.
22. An igniter having an ignition chamber, a filament therein, means for applying an electric current thereto, a baffle between said filament and the gas supply, and one or more inlets adjacent said filament and opening directly to the atmosphere for admission of atmospheric air thereto, substantially as set forth.
23. A burner head, an ignition chamber having an inlet in the path of gas issuing from said burner head, an ignition filament within said chamber and a baffle between said filament and said burner head and adjacent the filament, substantially as set forth.
24. In a gas lamp, a gas supply having an outlet, an ignition chamber having an inlet in the path of gas issuing from said outlet, an ignition filament within said chamber, and a baffle between said filament and said gas outlet and adjacent the filament, substantially as set forth.
25. In a gas lamp, an ignition chamber, a filament therein, means for applying an electric current thereto, and a baffle between said filament and the gas supply and adjacent the filament, substantially as set forth.
26. In a gas lamp, ignition means comprising a catalytic filament, means for applying an electric current thereto, means for setting up in the vicinity of the said filament a current of air and gas mixture and for directing the same past the filament at one side thereof, said means serving also to direct toward said filament a current of atmospheric air transverse to said current of air and gas mixture, substantially as set forth.
27. In a gas lamp, ignition means comprising a catalytic filament, means for applying an electric current thereto, means for directing toward said filament a current of atmospheric air and a distinct current of air and gas mixture moving transversely thereto and for preventing said currents from 125

mixing prior to arriving in the immediate vicinity of the filament, substantially as set forth.

28. The method of ignition which consists in warming a catalytic filament by an electric current, directing toward said filament a current of atmospheric air and a distinct current of air and gas mixture, said currents approaching said filament from 10 different directions and being prevented from mixing prior to arriving in the immediate vicinity of the filament, substantially as set forth.

29. In a gas lamp, the combination of a 15 burner head, a canopy above the same and provided with an aperture, an ignition chamber having a gas inlet communicating with said aperture, an air inlet, and a heated filament adjacent thereto, said moving gas

and heated filament acting in conjunction to 20 draw air through said air inlet, substantially as set forth.

30. In a gas lamp, the combination of a burner head, an ignition chamber having a gas inlet above the level of said burner head 25 and an air inlet, a conductive filament in said chamber adjacent said air inlet, and a baffle between said filament and said gas inlet, whereby the filament when heated causes air to be drawn into the chamber through 30 said air inlet, substantially as set forth.

This specification signed and witnessed this 28th day of Jan. 1910.
